UNITED STATES PATENT OFFICE.

PERRIN F. LEWIS, OF JAMESTOWN, NEW YORK.

DESIGN FOR AN AIR-CHAMBER FOR PUMPS.

SPECIFICATION forming part of Design No. 24,411, dated June 18, 1895.

Application filed February 25, 1895. Serial No. 539,875. Term of patent 7 years.

To all whom it may concern:

Be it known that I, PERRIN F. LEWIS, a citizen of the United States, residing at Jamestown, in the county of Chautauqua and State of New York, have invented a certain new and useful Design for an Air-Chamber for Spray-Pumps; and I do declare the following to be a full, clear, and exact description of the invention, such as will enable others skilled in the art to which it appertains to make and use the same, reference being had to the accompanying drawing, and to the letters of reference marked thereon, which forms a part of this specification.

15 The leading feature of my design consists of the slightly depressed spherical member G having about its largest circumference a

raised band H having right angled edges, a cylindrical projection rising from the upper pole, a short distance thence contracted and 20 slightly tapering to an end which is formed into a bead.

Having thus described my invention, what I claim to be new, and desire to secure by Letters Patent, is—

The design for an air chamber for a pump, as herein shown and described.

In testimony whereof I affix my signature in presence of two witnesses.

PERRIN F. LEWIS.

Witnesses:

CLINTON M. LEWIS,
FRANK E. SESSIONS.
